UNITED STATES PATENT OFFICE

170,789

RADIO-PHONOGRAPH CABINET PANEL

Samuel E. Adler, Chicago, Ill., assignor to Admiral Corporation, Chicago, Ill., a corporation of Delaware

Application June 4, 1953, Serial No. 25,314

Term of patent 14 years

(Cl. D56—4)

To all whom it may concern:

Be it known that I, Samuel E. Adler, a citizen of the United States, residing at Chicago, in the county of Cook, State of Illinois, have invented a new, original, and ornamental Design for a Radio-Phonograph Cabinet Panel, of which the following is a specification, reference being had to the accompanying drawing forming a part hereof.

Fig. 1 is a front elevational view of a radio-phonograph cabinet panel, showing my new design;

Fig. 2 is a top plan view of the same;

Fig. 3 is a sectional view taken on line 3—3 of Fig. 1;

Fig. 4 is a sectional view taken on line 4—4 of Fig. 1; and

Fig. 5 is a fragmentary sectional view taken on line 5—5 of Fig. 1.

The dominant features of my new design reside in that portion shown in full lines on the drawing.

I claim:

The ornamental design for a radio-phonograph cabinet panel, as shown and described.

SAMUEL E. ADLER.
